OTTO GOTTKÉ, OF HALENSEE, NEAR BERLIN, GERMANY.

PETROLEUM INCANDESCENT LAMP.

1,089,546.

Specification of Letters Patent. Patented Mar. 10, 1914.

Application filed September 8, 1913. Serial No. 788,676.

To all whom it may concern:

Be it known that I, Otto GOTTKÉ, a citizen of the German Empire, residing at Halensee, near Berlin, Germany, have invented certain new and useful Improvements in or Relating to Petroleum Incandescent Lamps, of which the following is a specification.

This invention relates to a petroleum incandescent lamp fed by a head of fuel, and in which the supply of air to the burner chiefly takes place through the mixing tube from the outside of a glass bell.

The object of this invention is to insure the reliable working of lamps of this kind and more particularly to make them non-sensitive to external low temperatures. To that end, care is taken in the new lamp to expel the liquid fuel contained in the superheater pipe coil at the beginning of working, by the action of vapors produced by the heating of the vaporizer and to introduce it into a liquid separator, in order to condense the incoming petroleum vapors in the said separator at the beginning of the evaporation, and thus to retard the vapor supply to the pipe section leading to the nozzle, until all vapor-conveying pipes have been heated sufficiently strongly to avoid condensation. For receiving the liquid fuel in the superheater pipe coil at the beginning of the working, there is arranged in the interior of the solid foot of the chimney, an annular tank engaging with its outer wall the inner wall of the said foot above the cup for the fuel for the warming up flame.

In order to insure quick and reliable ignition of the main flame, care is taken to provide a separate ignition flame supplied with fuel from the warming-up cup. The feeding of this ignition or by-pass flame is effected by a vaporizer secured to the warming cup and provided with a removable upper part. The ignition flame pipe is arranged in the latter in such a manner that when the cup is placed on the gasifier, it forms a resistance in order to avoid closing of the gas outlet opening by the porous material.

In order to prevent disturbing outer air from getting to the edge of the glass bell, the bell ring supporting the bell and hinged to the lamp reflector, is provided with two grooves directed in opposite directions, for receiving packing material, and is made in two sections, so that the lower part detach-

ably mounted on the part hinged directly to the reflector, can press the edge of the glass bell against the packing material in the downward groove of the upper part. 60

A construction according to this invention is illustrated in the accompanying drawing, in which,—

Figure 1 is a central vertical section through a lamp constructed in accordance 65 with the invention; Fig. 2 is a top view of a part of the reflector of the lamp; and Fig. 3 is a sectional view of the means used for connecting the lamp globe with the reflector.

A solid base 1 forms a support for the 70 main parts of the lamp. On the said base is mounted the foot 2 of the chimney 3, so that the chimney can be raised with its foot, in order to enable the evaporating device to be easily removed. The evaporating pipe 4 75 is directly connected, by means of a right angle bend 5, to a superheater pipe coil 6 which is carried upward in the annular fuel tank 7 to a point above the level of the fuel and provided with an opening 8. The fuel 80 is conveyed from the tank 7 to the vaporizer 4 through the pipe 9, which is provided in any desired manner with a closing valve 10.

11 is the annular liquid separator inserted in the solid foot 2 of the chimney and engaging with its outer wall against the part 85 2. The superheater pipe 6 opens with its downward branch into the tank 11. The fuel vapors are conveyed from the tank 11 through the pipe bend 12 and pass through 90 a pipe 13 arranged transversely below the chimney, into the nozzle 14. The section of the pipe 13 arranged in front of the nozzle 14, is mounted in a box-shaped projection 15, 16 of the foot 2 of the chimney and of 95 the base 1, so that those portions of the pipe, adjoining the nozzle are exposed, to the waste heat. In the base 1 is arranged the annular warming up cup 17, through the bottom of which passes a ring of tubes 18 100 open on both sides and used for supplying air to the warming up flame and giving the latter the nature of a ring flame. The air is taken from the interior of the glass bell or globe 19 into which it passes to a limited extent through openings 20 at the lower end of the globe. The mixing tube 21 is secured to the reflector 22, and opens outside the glass globe. The globe itself is secured to the reflector by means of a two-sectioned metal 110 ring 23, 24 hinged to the reflector. The metal ring 23 is provided with two grooves

105

25, 26 for receiving packing material above and below. The globe 19 is pressed by the part 24 detachably secured to the part 23, against the packing material in the groove, 5 26, so that any passage of air along the ring and the edge of the globe into the interior of the globe is avoided. The division of the globe ring into two, makes it possible to replace in a simple manner a broken 10 globe by simply unscrewing the part 24 from the part 23, without it being necessary to cover the globe again with a metal net, as the metal net 27 is supported by the detachable ring portion 24 and can be lifted 15 off with the same from the globe.

The globe is perforated at the lower end and provided with a downwardly projecting insertion 28 protecting the air inlet openings 20 from draft. Over the bottom 20 end of the globe a drip cup 29 projects screwed to the bottom portion 30 of the mixing tube. The burner 31 is shown as having an upright incandescent mantel 32.

On the upper side of the reflector 22 a 25 protecting casing 33 is mounted provided with openings 34 for admitting fresh air. The reflector is also provided at its outer edge with air inlet openings 35. An ignition flame evaporator 36 is secured to the 30 warming up cup 17 and provided with fuel inlet openings 37. The ignition flame tube is marked 38. The filling pipe for the warming cup is marked 39.

The working and the manipulation of the 35 lamp are as follows:—The valve 10 having been opened, the fuel from the tank 7 will pass through the pipe 9 and the evaporator 4 into the rising pipe of the superheater pipe coil 6. If the fuel in the warming cup 17, 40 is then lighted, the fuel contained in the evaporator and at the lower end of the rising branch of the superheater pipe coil 6, begins to evaporate. The vapors produced force the liquid fuel contained in the rising 45 branch of the superheater pipe 6 out of the pipe, so that it is projected into the liquid separator 11. Here it remains for a time, and owing to its comparatively low temperature, brings about condensation of the vapors 50 first arriving through the superheater pipe 6, so that the feeding of the pipe sections 12, 13 and of the nozzle 14 is at first retarded. In the meantime, owing to the energetic action of the warming up flame, all gas con- 55veying portions of the piping and of the liquid separator 11 will be further heated, so that finally a state is reached, in which the vapors passing from the superheater pipe coil 6 into the tank 11, are no longer 60 condensed, but pass in the form of strongly superheated vapors into the pipe sections 12, 13 and to the nozzle 14. The vapors carry away with them from the inner space of the casing 33, warmed fresh air admitted 65 through the openings 34, 35. The mixture

of air and vapors passes into the mixing tube 21 and from the latter to the burner 31. Any portions still condensing, are received by the drip cup 29. During the preliminary heating liquid fuel passes from the 70 warming cup 17 through the openings 37 into the ignition flame evaporator 36 and is here evaporated, so that through the ignition flame pipe 38 combustible vapors escape which are ignited by the warming up 75 flame, so that an ignition flame directed downward is produced and can light the main flame.

Owing to the special shape of the liquid separator and its arrangement at the foot of 80 the chimney, both the gases of the warming up flame and the waste gases of the main flame, owing to the energetic suction produced by the long chimney, heat the surface of the inner wall and the bottom of the 85 liquid separator in such a manner that only strongly superheated and dried vapors can reach the nozzle. As is well known, solid coke-like residue is separated from the petroleum by such strong superheating. In 90 order to prevent the said residue from interfering with the escape of gas from the nozzle, the gas outlet in the liquid separator is arranged at the highest possible level. Thus the injurious residue is deposited in the 95 liquid separator.

When the globe 19 breaks, the ring portion 24 is unscrewed, so that the globe 19 can be removed together with the protecting net 27. A new globe can be thereupon inserted into 100 the protecting net, and the ring portion 24 again screwed to the ring portion 23.

I wish to be understood that the lamp construction above described may be modified without leaving the scope of my invention. For instance tubes 18 in the warming up cup may be dispensed with and the pipe bend 12 may be connected to the nozzle 14 in any appropriate way without providing 105 the box-shaped extension 15, 16. 110

What I claim is:—

1. In a petroleum incandescent lamp provided with a chimney, a burner, an evaporating pipe, a fuel tank connected thereto and positioned at a higher level than the evaporating pipe, a superheater pipe coil having one end connected to said evaporating pipe and rising upward beyond the level of the fuel in the tank, a substantially annular liquid separator receiving the outlet end of 115 said superheater pipe coil the central space inclosed thereby forming the entrance of the chimney, a conduit adapted to carry the fuel vapors from said liquid separator to said burner, and a warming up cup, the liquid 120 separator being disposed above said evaporating pipe and warming up cup.

2. In a petroleum incandescent lamp giving an intense light, a burner, an evaporating pipe, a fuel tank connected thereto and posi- 130

tioned at a higher level than the evaporating pipe, a superheater pipe coil having one end connected to said evaporating pipe and rising upward beyond the level of the fuel in 5 the tank, a substantially annular liquid separator receiving the outlet end of said superheater pipe coil, a conduit adapted to carry the fuel vapors from said liquid separator to said burner, a chimney surrounding the superheater pipe coil and the liquid separator, a base member carrying the 10 gasifying device and the warming up cup, the foot of said chimney being detachably mounted on said base member and with its inner wall substantially in contact with the outer wall of the annular liquid separator and a warming up cup, the liquid separator 15 being disposed above said evaporating pipe and warming up cup.

3. In a petroleum incandescent lamp giving an intense light, a burner, an evaporating pipe, a fuel tank connected thereto and positioned at a higher level than the evaporating pipe, a superheater pipe coil having 20 one end connected to said evaporating pipe and rising upward beyond the level of the

fuel in the tank, a substantially annular liquid separator receiving the outlet end of said superheater pipe coil, a conduit adapted to carry the fuel vapors from said liquid separator to said burner, a chimney surrounding the superheater pipe coil and the liquid separator, a base member carrying the 25 gasifying device and the warming up cup, the foot of said chimney being detachably mounted on said base member and with its inner wall substantially in contact with the outer wall of the annular liquid separator and a warming up cup, the liquid separator 30 being disposed above said evaporating pipe and warming up cup.

In testimony whereof, I affix my signature in presence of two witnesses.

OTTO GOTTK.
